COMBINED BIRTH RECORD AND PICTURE FRAME

Victor M. Kindlund and Cleatus S. Kindlund, both of 296 Oaklawn Ave., Cranston, R.I.

Filed Nov. 26, 1963, Ser. No. 77,568

Term of patent 14 years

(Cl. D29—20)

FIG. 1

FIG. 2

FIG. 3

FIG. 4

FIG. 5

FIG. 1 is a front elevational view of a combined birth record and picture frame, showing our new design;

FIG. 2 is a rear view thereof;

FIG. 3 is a side view thereof;

FIG. 4 is a sectional view taken through line 4—4 of FIG. 1; and

FIG. 5 is a sectional view taken through line 5—5 of FIG. 2.

The characteristic features of our design reside in the portions shown in full lines.

We claim:

The ornamental design for a combined birth record and picture frame, substantially as shown and described.
